US00D900786S

(12) **United States Design Patent** (10) Patent No.: **US D900,786 S**
(45) Date of Patent: **** Nov. 3, 2020**

(54) **SOUND BAR**

(71) Applicant: **LG ELECTRONICS INC.**, Seoul (KR)

(72) Inventors: **Yongsoo Kim**, Seoul (KR); **Sungyong Park**, Seoul (KR); **Junki Kim**, Seoul (KR)

(73) Assignee: **LG ELECTRONICS INC.**, Seoul (KR)

(**) Term: **15 Years**

(21) Appl. No.: **35/506,896**

(22) Filed: **Dec. 10, 2018**

(80) **Hague Agreement Data**

Int. Filing Date: **Dec. 10, 2018**

Int. Reg. No.: **DM/200339**

Int. Reg. Date: **Dec. 10, 2018**

Int. Reg. Pub. Date: **Jun. 14, 2019**

(30) **Foreign Application Priority Data**

Jun. 19, 2018 (KR) 30-2018-0028258

(51) **LOC (12) Cl.** **14-01**

(52) **U.S. Cl.**

USPC **D14/214**; D14/204

(58) **Field of Classification Search**

USPC ... D14/172, 188, 194, 204, 209.1, 211, 214, D14/221

CPC H04R 2420/07; H04R 5/02; H04R 1/403; H04R 2201/028
